(57) **CLAIM**

The ornamental design for an ultrasound biopsy probe, as shown and described.

DESCRIPTION

FIG. 1 is a top perspective view of an ultrasound biopsy probe, showing our new design;

FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The needle assembly, collection assembly, latch assembly, and gears shown in broken lines are unclaimed subject matter and form no part of the claimed design.
